UNITED STATES PATENT OFFICE.

THOMAS J. HART, OF BUFFALO, NEW YORK, ASSIGNOR TO SHERWOOD MANUFACTURING COMPANY, OF BUFFALO, NEW YORK.

LUBRICATOR.

SPECIFICATION forming part of Letters Patent No. 779,039, dated January 3, 1905.

Application filed January 7, 1904. Serial No. 188,100.

To all whom it may concern:

Be it known that I, THOMAS J. HART, a citizen of the United States, residing at Buffalo, in the county of Erie and State of New York, have invented new and useful Improvements 5 in Lubricators, of which the following is a specification.

This invention relates more particularly to a lubricator of that type in which a pump is 10 employed which takes the lubricant from a reservoir or source of supply and forces it to the part to be lubricated.

The object of the invention is to provide a lubricator of this type of simple and desirable 15 construction in which the feed of the lubricant is at all times under the inspection and control of the attendant without disturbing the operation of the pump, in which the feed will remain constant when adjusted regardless 20 of the diminishing supply of lubricant, and in which the feed will stop, so as not to waste the lubricant when the machine or part being lubricated comes to rest.

In the lubricator hereinafter described as 25 an embodiment of the invention the lubricant is taken from a reservoir or supply source by a pump and forced up into an auxiliary reservoir, from which it is taken by said pump and forced to the part to be lubricated, the supply passing down through a sight tube or 30 chamber, which enables an inspection of the feed.

In the accompanying drawings, consisting 35 of two sheets, Figure 1 is a vertical sectional elevation of a lubricator embodying the invention. Fig. 2 is a horizontal section thereof in line 2 2, Fig. 1. Fig. 3 is a plan view of the reservoir with the cover removed. Fig. 4 is a section through the pump-operating 40 mechanism in line 4 4, Fig. 2. Fig. 5 is a section through the friction-clutch in line 5 5, Fig. 4. Fig. 6 is a vertical sectional elevation of a modified construction.

Like letters of reference refer to like parts 45 in the several figures.

Referring particularly to Figs. 1 to 5, A represents a lubricant-reservoir or supply-receptacle, which is preferably in the form of the ordinary oil-cup, composed of a base *a*, a 50 top ring or portion *a'*, connected to the base

by a central column *a*², and a hollow glass or transparent body portion *a*³, clamped between the base and the top ring. The top ring is provided with arms *b*, radiating from a central hub, which is hollow and surrounds a reduced upper portion of the central column, to which it is rigidly clamped between a nut *b'*, working on the threaded upper end of the column, and a shoulder at the base of the reduced portion of the column. C represents a 60 reservoir - cap which is screwed upon the threaded upper end of the column, and *c* a strainer for the lubricant, which is preferably clamped between the top ring and body of the reservoir. These parts may be of any other 65 suitable construction—for instance, as shown in the construction illustrated in Fig. 6. D represents the pump-cylinder, and E a piston or plunger which is arranged to reciprocate in the cylinder. The cylinder is formed integrally with the base of the lubricant-reservoir and extends diametrically across the same. The cylinder has a main piston-chamber *d* and an auxiliary piston-chamber *d'*, preferably of 70 smaller diameter than and in line with the main piston - chamber. The plunger is provided with a piston or portion which works in the main piston - chamber and with an auxiliary piston or portion which fits and works in the auxiliary piston - chamber. The two piston-chambers are preferably separated by a packing-gland *e*, surrounding the auxiliary piston. 75 *f* represents one or more induction or inlet ports for admitting the lubricant from the reservoir into the main piston-chamber intermediate of its ends. While the pump-cylinder shown constitutes a part of the supply-reservoir and communicates directly therewith by the port *f*, this construction is not 80 essential, for the cylinder can be independent 85 of the reservoir and connected with a distant source of supply. The column is hollow and constitutes a stand-pipe for the lubricant. The stand-pipe communicates at its lower end with the forward end of the main piston-chamber by a port *g*, controlled by a gravity-valve *g'*, and its upper end communicates by lateral passages with an annular chamber *g*², formed between the reduced upper end of the stand-pipe and the hub of the top ring of the 90 95 100

reservoir. One of the radial arms of the top ring is hollow or provided with a supply-passage H, which connects at its inner end with the annular chamber of the hub and at its outer end with the chamber i of a hand controlling-valve I. The radial arm is also provided with a return or overflow passage h, connecting with the supply-passage H and arranged to discharge into the reservoir. The hand-valve controls the passage of a nozzle K, depending from the valve-chamber. A screw-plug or needle-valve is shown provided at its upper end with a knurled head or the like for turning it and a nut for locking it in adjusted positions. The valve-chamber constitutes an integral part of the top ring of the reservoir. The nozzle K extends down into the upper end of a vertical tube or chamber L, the lower end of which communicates through a passage l and port l', formed in the base of the reservoir, with the auxiliary piston-chamber d' of the pump. The vertical tube is preferably transparent and forms a sight-tube enabling the attendant to see at all times whether or not the lubricant is properly feeding. It is provided at its upper end with a vent-hole l''. M represents a nipple for the attachment of a discharge-pipe leading to the part to be lubricated. The nipple is connected to the reservoir-base by a suitable union and connects by a passage m with the front end of the auxiliary piston-chamber of the pump. The passage l, leading from the lower end of the sight-tube, is controlled by an upwardly-seating check-valve N, and the passage m, connecting the front end of the pump-cylinder with the discharge-pipe, is controlled by an inwardly-seating check-valve O. Ball-valves are shown which are moved to their seats by suitable springs.

The pump-plunger is reciprocated by suitable means, and at each rearward movement the main piston draws a quantity of lubricant from the reservoir through the induction-port f into the main piston-chamber and upon the forward stroke the lubricant so drawn into the piston-chamber is forced into the stand-pipe past the check-valve at its lower end. The lubricant accumulates in and fills the stand-pipe and supply-passage H, which thus constitute a supplemental reservoir or supply-receptacle which is kept filled to the same extent regardless of the quantity of lubricant in the main reservoir. When the regulating-valve I is off of its seat, the lubricant will drop or flow from the nozzle K down through the sight-tube, and at each rearward movement of the auxiliary pump-piston a predetermined quantity of lubricant will be drawn past the check-valve N into the auxiliary piston-chamber and forced past the check-valve O into the pipe leading to the part to be lubricated.

The quantity of lubricant fed by the piston can be regulated accurately by the adjustment 65 of the hand controlling-valve I without alter-

ing the operation of the pump, and if more lubricant is supplied to the stand-pipe than can pass the valve it flows back into the reservoir through the return-passage h, or the feed can be entirely shut off by the valve I. 70 without stopping the pump, in which case the pump will circulate the lubricant from the reservoir through the stand-pipe and return-passage back to the reservoir. As the lubricant is fed from the stand-pipe to the part to 75 be lubricated the quantity fed is in no wise dependent on or affected by the changes in quantity and weight of the lubricant in the reservoir, and the feed is always constant. If the engine or machine being lubricated is 80 stopped, the pump will come to rest and there can be no waste of lubricant by gravity from the reservoir whether or not the attendant neglects to close the regulating-valve. As the lubricant is drawn positively from the sight-tube by the pump the oil cannot fill the tube and cloud the glass, and thus prevent the inspection of the feed.

Any suitable speed-reducing mechanism may be employed for connecting a moving 90 part of the engine or machine to be lubricated with the pump piston or plunger to reciprocate the latter. The mechanism shown in the drawings for this purpose is constructed as follows: The stem of the pump-plunger extends rearwardly through a suitable packing-gland p on the cylinder and is guided in a bearing p' on a bracket or arm P, projecting from the reservoir-base. The bearing-arm is perforated at its inner end and engaged over a depending central stud p'' on the reservoir-base, on which it is secured by a nut p'', screwed on the threaded end of the stud. The nut p'' is also threaded and serves for securing the reservoir stationarily on a suitable support. 105 The bearing-arm is also secured to the reservoir-base by a screw p''. Q represents a shaft journaled to rotate in a bearing q on the bearing-arm P and having formed therewith or secured thereto a crank-wheel q', provided with a crank-pin q'', which enters a transverse slot r in a collar R, adjustably secured on the plunger-stem by a set-screw or the like r'. S is a disk secured to the shaft Q and constituting one member of an ordinary ball or roller 115 friction-clutch, the other member, s, of which consists of a cylindrical casing journaled on the shaft and inclosing the clutch-disk and the friction-roller s', which is located in a wedge-pocket in the disk and pressed toward the 120 clutch-casing by a suitable spring. T is an operating-rod which is secured to the clutch-casing and is connected in any suitable manner to and operated by the engine or machine being lubricated. The end of the shaft Q is 125 also preferably squared for the engagement of a crank or tool, whereby the shaft and pump can be operated manually when desired.

While the invention is described in connection with a lubricator, it may be used for other 130

purposes where it is desired to feed a fluid and have the feed at all times under the control and inspection of the attendant. For instance, the device could be used to feed water to a 5 steam-boiler or the like.

The lubricator shown in Fig. 6 is similar to that above described except in details of construction and in the fact that the stand-pipe U and horizontal supply-passage H' consist of 10 separate pipes instead of being formed by the central column and top ring-arm of the reservoir.

I claim as my invention—

1. The combination of a supply-reservoir for the liquid, a pump which communicates with and takes the liquid from said reservoir, a stand-pipe arranged within said reservoir and into which said pump forces the liquid taken from said reservoir, a sight-tube arranged exteriorly of said reservoir, a part having a passage connecting the upper portion of the sight-tube with said stand-pipe, there being a valved communication between the lower end of said sight-tube and said pump, whereby said pump draws the liquid from the lower end of said sight-tube, and means provided with a discharge-passage through which said pump forces the liquid taken from said sight-tube, substantially as set forth. 15
2. The combination of a supply-reservoir for the liquid, a pump which communicates with and takes the liquid from said reservoir, a stand-pipe arranged within said reservoir and into which said pump forces the liquid taken from said reservoir, a sight-tube arranged exteriorly of said reservoir, a part having a passage connecting the upper portion of the sight-tube with said stand-pipe, there being a valved communication between the lower end of the sight-tube and said pump, whereby said pump draws the liquid from the lower end of said sight-tube, and means provided with a discharge-passage through which said pump forces the liquid taken from said sight-tube, substantially as set forth. 20
3. The combination of a supply-reservoir for the liquid, a pump having a piston-chamber formed in the base of said reservoir and which has an inlet-port communicating with said reservoir, and a second piston-chamber, a stand-pipe arranged within said reservoir 25 and having a valved communication at its lower end with said first-mentioned piston-chamber, a vertical sight-tube arranged exteriorly of said reservoir and having a valved communication at its lower end with said second piston-chamber, a part having a passage connecting the upper ends of said stand-pipe and sight-tube, a hand-valve controlling the communication between said sight-tube and said passage, means provided with a discharge-passage, and a double pump-piston 30 working in said piston-chambers and which draws the liquid from said reservoir, forces it up into said stand-pipe, draws it from said sight-tube, and forces it through said discharge-passage, substantially as set forth. 35
4. The combination of a supply-reservoir for the liquid having a hollow column which connects parts of the reservoir and constitutes a stand-pipe for the liquid, a pump which communicates with and takes the liquid from said reservoir and forces it into said stand-pipe, a sight-tube communicating at its upper portion with the upper portion of said stand-pipe and at its lower end with said pump whereby the latter draws the liquid from said sight-tube, and means provided with a discharge-passage through which the pump forces the liquid taken from said sight-tube, substantially as set forth. 40
5. The combination of a supply-reservoir for the liquid having upper and lower detachable parts and a hollow column which connects said parts of the reservoir and constitutes a stand-pipe for the liquid, a sight-tube communicating at its upper portion with the upper portion of said stand-pipe, and means for taking the liquid from said reservoir, delivering it to said stand-pipe, and taking the liquid from the lower portion of said sight-tube and feeding it to another part, substantially as set forth. 45
6. The combination of a supply-reservoir for the liquid consisting of a base, a top ring, and a body, a hollow column connecting said base and top ring and constituting a stand-pipe for the liquid, a sight-tube, said top ring having a passage connecting the upper portion of said sight-tube with the upper portion of said stand-pipe, and means for taking the liquid from said reservoir delivering it to the stand-pipe, and taking the liquid from said sight-tube and feeding it to another part, substantially as set forth. 50

Witness my hand this 30th day of December, 1903.
